G. E. Maynard,
ATTORNEY.

UNITED STATES PATENT OFFICE

JOSEPH BLONDIN, OF LOS ANGELES, CALIFORNIA

UNI-LAYER RIGID AIRPLANE WING

Application filed July 9, 1929. Serial No. 376,917.

This invention relates to airplane wings and to "control" surfaces for airplanes.

An object is to provide features which will be superior in point of simplicity, low cost, 5 rigidity, durability, safety and general serviceability.

More particularly an object is to provide a substantial and practicable uni-layer or monoply-body supporting surface as distinguished from all forms of airplane wing and control planes embodying more than one ply in the body, whether laminated or interstitial. In this connection it is, further, an object to provide an unilayer surface (used 15 in the aeronautical sense) which is inherently rigid and capable of holding, normally, its shaped form.

A further and predominant object of the present concept is to provide a supporting 20 surface designed to produce peculiar and advantageous air-flow reactions on its lower and its upper faces.

Other objects, advantages and features of construction, combination and detail members and certain characteristics will be made 25 manifest in the ensuing description of the herewith illustrative embodiment; it being understood that modifications, variations and adaptations may be resorted to within the 30 scope, principle and spirit of the invention as it is more directly claimed hereinafter.

Figure 1 is a top plan of the improved wing or surface.

Figure 2 is a bottom plan thereof.

Figure 3 is a cross-section.

The wing proper consists of a single structural sheet 2 of any approved, inherently rigid material which may be stamped, bent, cast or cut to and will normally retain its 40 desired or given curvature; i. e., will hold its shape prior to attachment or incorporation of certain wing-bars and ribs.

To the ventral, concaved face A, which reacts to sustain a load, in flight, there is attached a series of generally parallel wing-bars or beams 3 lengthwise of the wing and in any preferred lateral spaced relation to each other. These are thin vertically and of streamline design.

50 A plurality of ribs 4 is applied dorsally

and transversely to the top of the wing in any desired mutual spaced order.

The advantages and superiority with reference to prior practice in airplane wing construction is that by utilizing an inherently 55 rigid surface this precludes the many qualities of deficiency concomitant with all forms of fabric and relatively flexible or pliant material of any kind and differentiates the invention from early type "single-surface" fabric 60 wings which anticipate this invention in appearance only and whose very lack of the qualities and features this invention brings to the art of wing construction resulted in their early abandonment in favor of the 65 "double-surfaced wings" universally used at this period.

Single-surface fabric covering stretched between or stretched over the ribs in early type airplane wings were characterized by 70 the following defects: The covering was so flexible and subject to extension and sagging, under air pressure, as to present and maintain a very inefficient and constantly varying aerodynamic curve to the air, resulting in comparatively poor lifting quality;—the flexibility and give of the fabric precluded the acquisition of any aerodynamic data to govern 75 the study and development of wing-curves and their relative characteristics. Wind-tunnel tests and progress in the art of designing wing curves dates only from the time "single-surface" textile wing-covering was abandoned in favor of "double-surfaced" 80 wings.

Further, the flexible single-surface wing-covering lent no factor of strength to the wing structure proper, in fact the necessity of lacing and stretching said surfaces to the ribs and to wing-spars introduced added 90 stresses tending to weaken the ribs and spars; also, the fabric covering was placed over the ribs or the ribs extended in depth as much below as above the fabric cover and this robbed the wing, per se, of a valuable—not to 95 saw fundamental—feature of levitation capable of being derived from play or action of air-current above and over a wing and which action was little understood, therefore ignored, in the design of such early-type 100

wing, but which I have carefully studied and which is a governing factor in the design of the wing forming the present invention.

5 Today the science of aerodynamics concerned in the design of wing-curves and their relative characteristics proves that a wing-lift is greater-or-less in proportion to the difference of velocities of air-flow that are 10 caused to sweep across the dorsal and ventral faces respectively. The faster the flow of air over a wing and the slower, relatively, under the wing at the same and equal periods of time, the greater will be the suction 15 over the surface and the greater will be the lift furnished by the wing. Non-technically stated, a wing functions as follows: Upon 20 propulsion its under, concave face impinges against, slows up and even carries along the air it encounters in its line of flight, whereas its upper, convex face at the same time recedes from, and accelerates the air from said top face. The most efficient lifting wing will be one which is designed to effect the maximum 25 acceleration of the air flow over its upper face and a maximum retardation of the air flow under its lower face during an equal lapse of time.

It is this application of aerodynamic law 30 that explains the curve path of a "spit-ball" thrown by a base-ball pitcher,—the sustention of a ball in a jet of water against the pull of gravity and the whole art of aviation by means of airplanes.

35 (This elucidation of the action of air currents upon and around the wing in travel is technically known as "Prandtl's boundary layer theory" in aerodynamics; and in ballistics as the "Magnus effect.")

40 The art of wing design, therefore, rapidly took the form of "double-surface" covering whose top and bottom face curvatures could be more positively maintained and studied, and whose structural elements or frame work 45 could be contained between coverings and withdrawn from head-on and frictional resistance against the air. Experience soon developed the fact that this type of wing was more efficient the more rigidly it was constructed, which led, finally, to the introduction 50 of abnormally thick wings, permitting great latitude in design of strong, rigid, wing spars so generally adopted today. The overall efficiency of these thick wings is relatively high due, not to the thickness itself 55 which is a harmful factor involving the displacement of an equal bulk of air and absorbing much power in the effort, but more certainly to the rigidity of the element and 60 to the greater difference of relative curvatures, made possible by the thickness: the differences favoring the formation of "Prandtl vortices".

With these general principles in mind I 65 desire to particularly call attention to the

fact that the instant invention involves a design of wing wherein: great rigidity is obtained by the choice of a stiff-body material produced, by appropriate mode, to a selected curve of known aerodynamic characteristics and capable of maintaining such 70 curve independently of extraneous constructional elements: The choice of material, rigid in itself, will permit a more thorough and searching study of aerocurve characteristics 75 and lead to the production of maximum efficiency in wing design: The rigid, mono-layer wing of determined, constant, arcuate shape becomes, in itself, a solid, minimum depth, integral-body wing-spar cooperating with the associated spar elements proper of the 80 structural frame and lending strength and resistance to bending along its length and with the frame of ribs and spars lending resistance to drag and torsional stresses as 85 well: Unlike single-layer fabric wings, this invention discloses the application of the ribs to the upper face of the mono-layer, rigid body exclusively designed for the purpose of forming transverse ridges which constrain 90 the air to flow in channels therebetween and directly across the wing in the shortest possible path along the line of flight.

On the other hand the set of wing-spars 95 extending longitudinally of and under the wing sheet effect a slowing up of the air-flow by direct resistance and diverting said flow laterally outward towards the wing tips thus making the air-flow take a resultant diagonal path as long and as retarded as possible under the wing. These wing-spars are not, of course, designed for direct head resistance 100 but are properly stream-lined and do not add as much resistance to propulsion as do the thick, double surfaced wings of conventional 105 airplanes in the displacement of their equivalent bulk of air. The wing-spars are to be distinguished from and contrasted with the conventional practice of using only two (front and rear) wing-spars because this invention contemplates the use of more than 110 two spars of thin vertical depth in association with "window-frame" struts such as are set out in my Patent #1,240,812, of Sept. 25, 1917, which form alone of all known types 115 favors use of front and rear and intermediate spars by providing a support therefor on the stringer of the "window-frame."

The thin, rigid, single-layer wing of this invention affords maximum efficiency as an 120 aerodynamic surface and is stronger, simpler, cheaper and easier to handle in the set-up and knock-down of a machine than any other type of equal surface designed to date and possesses the vitally important advantage of 125 insuring safety since it exposes at all times every element of construction of the complete wing. This feature, particularly, provides the possibility of constructing ideal seaplane wings free from rapid deterioration 130

suffered in the conventional types and produced by condensation of moisture which affects the entire interior of all hollow wings and the enclosed parts; such wings precluding internal inspection and timely remedy of critical conditions.

In contrast to the concealed condition of all interior parts and surfaces of hollow wings the present wing body can be freely 10 inspected at all times, when not in actual flight, without necessitating dismounting or manipulation of any parts, and those defective in any degree may be discovered and repaired or replaced with little loss of time 15 because of accessibility and visibility.

As examples of appropriate stiff-body material for the supporting surface may be mentioned sheet-metal, bakelite, fibre and plywood.

20 What is claimed is:

1. An airplane supporting surface consisting of a thin, single layer, solid body of rigid, spar-forming character and having a series of longitudinal, ventral spars exposed to 25 air-flow and forming longitudinal channels endwise of the surface.

2. An airplane supporting surface consisting of a thin, single-layer, solid body of spar-forming character, and a plurality of 30 ribs fixed dorsally on the body-surface and forming ridges and channels from front to rear for determination of air-flow currents.

3. In airplane wing construction, a thin, rigid, single-layer supporting surface whose 35 top face is convex and has conforming, fore-and-aft ribs, and whose lower face has longitudinal wing-spars; said ribs and spars being exposed to constrain air-flow in differential channels along the top and the bottom 40 faces of the surface.

4. An airplane wing whose body is of solid, uni-layer, rigid form and has top ribs and bottom longitudinal spars, and whose structural entirety is fully exposed for ready 45 inspection and repair.

5. In airplane wing construction, a thin, rigid supporting surface whose top face is convex and presents uninterrupted fore and aft parallel air channels, and whose lower 50 face presents uninterrupted, parallel longitudinal air channels.

6. An airplane wing whose body is a solid, rigid form presenting unobstructed parallel, air channels from front to rear on its top 55 surface and co-extensive therewith, and whose bottom presents unobstructed, longitudinal, air channels from end to end, and whose structural entirety is fully exposed for ready inspection and repair.

60 JOSEPH BLONDIN.
